Primary Examiner—Cathron C Brooks*(74) Attorney, Agent, or Firm*—Merchant & Gould P.C.**CLAIM**

The ornamental design for pouch for holding liquids, as shown and described.

DESCRIPTION

The sole figure is a top plan view of a pouch for holding liquids, depicted in an unfilled (flat) configuration; the bottom plan view being a mirror image thereof; all side elevational views not shown and being devoid of ornamentation when in an unfilled (flat) configuration.
